CLAIM

The ornamental design for a suspended luminaire, as shown and described.

DESCRIPTION

FIG. 1 is a perspective view of a first embodiment of my new design;

FIG. 2 is a front elevational view of the first embodiment; FIG. 3 is a right side elevational view of the first embodiment, the left side being a mirror image thereof;

FIG. 4 is a rear elevational view of the first embodiment;

FIG. 5 is a top plan view of the first embodiment;

FIG. 6 is a bottom plan view of the first embodiment;

FIG. 7 is a perspective view of a second embodiment of my new design;

FIG. 8 is a front elevational view of the second embodiment; FIG. 9 is a right side elevational view of the second embodiment, the left side being a mirror image thereof;

FIG. 10 is a rear elevational view of the second embodiment;

FIG. 11 is a top plan view of the second embodiment; and,

FIG. 12 is a bottom plan view of the second embodiment.

The broken lines are shown for illustrative purposes only and form no part of the claimed design.
